UNITED STATES PATENT OFFICE.

OSCAR CARL NORTON, OF ROODHOUSE, ILLINOIS.

SIGHT-FEED DEVICE.

1,392,205.

Specification of Letters Patent. Patented Sept. 27, 1921.

Application filed May 7, 1920. Serial No. 379,605.

To all whom it may concern:

Be it known that I, OSCAR CARL NORTON, a citizen of the United States, and a resident of Roodhouse, in the county of Greene 5 and State of Illinois, have invented certain new and useful Improvements in Sight-Feed Devices, of which the following is a specification.

My invention is an improvement in sight 10 feed devices, and has for its object to provide a device of the character specified adapted for use with internal combustion engines, to feed water to the manifold, wherein the amount of water fed is under observation, 15 and can be easily regulated to the required amount.

In the drawings:

Figure 1 is a side view of a motor provided with the improved feed; 20 Fig. 2 is a vertical section through the feed;

Fig. 3 is an end view.

The present embodiment of the invention is shown in connection with the motor 1 of 25 a motor vehicle indicated at 2, the said motor being an internal combustion engine, and the intake manifold 3 of the motor is connected by a pipe 4 with the sight feed, the said feed also being connected by a pipe 5 30 with the connection 6 from the water circulation system of the motor to the radiator, indicated at 7.

The sight feed comprises a casing consisting of a body 8 and branches 9 and 9^a, 35 which extend substantially parallel with each other from the body. The body has threaded recesses 10 and 11 into which are threaded nipples 12 and 13, and the said nipples are connected to the pipes 4 and 5 40 before mentioned.

The branch 9 of the casing 8—9—9^a has a recess 14, and this recess communicates by a port 15 with the recess 10 before mentioned. The branch 9^a of the casing has a 45 recess 16 which communicates by a passage 17 with the recess 11 and a passage 18 leads from this recess 16 downwardly, delivering at the center of the recess 14 in the branch 9.

It will be noticed that the branch 9^a has 50 a nipple 19 forming an extension of the passage 18, and the lower end of this nipple 55 is near the top of the branch 9, but spaced far enough apart so that the feed through the nipple can be seen. The passages 15 and 60 17 are controlled by needle valves 20 and 21, respectively, which have threaded en-

gagement with openings in the branches 9 and 9^a, and the former valve controls the flow of the water to the pipe 4 from the recess 14, while the latter valve controls the 60 communication between the pipe 5 and the branch 9.

In operation, the water feeds from the connection 6 through the pipe 5, the nipple 13 into the passage or recess 11 of the casing, 65 from whence it flows by way of the passage 18 to the recess 14. From here the water flows by way of the passage 15 to the pipe 4 and to the intake manifold. The flow of the water may be nicely regulated by means 70 of the two valves, and when once regulated the feed is in sight, so that the driver has the feed always under observation. The casing 8—9—9^a is arranged on the dashboard 75 22 of the vehicle, as shown in Fig. 1, in convenient position for the driver's observation.

After the device is once set to the proper feed it is not necessary to change the same. When the circulating pump of the motor is working there will be a constant circulation 80 of water, but this circulation will stop when the pump stops, that is, when the motor stops.

The improved device is also adapted for use as a primer. On cold mornings, when 85 the motor usually starts with difficulty, the sight feed can be used to squirt a little gasoline into the cut or bowl. From there it will flow into the manifold and when the motor is turned it will start. This is especially 90 adapted for cars of the Ford class, which do not have priming cups.

As illustrated in Fig. 2, the upper end of the bowl 14 is entirely open and entirely 95 unobstructed so that a quantity of priming fluid may be readily introduced into the bowl for subsequent introduction into the intake manifold. Also, the suction created by the operation of the engine will draw a 100 quantity of air through the bowl and cause the air to enter the intake manifold for increasing the efficiency of the engine and economizing on fuel. The needle valve 20 may be conveniently regulated for admitting either water, air or gasoline to the pipe 4 105 which has communication with the bowl. Should it be desired to admit air only to the pipe 4, the upper needle valve 21 is seated so as to cut off the supply of water. The lower needle valve 20 is now unseated so 110 that the suction created by the operation of the engine will draw a quantity of air

into the pipe 4 from the bowl 14. The needle valve 20 may of course be regulated for controlling the quantity of air supplied.

Should it be desired to admit water only 5 to the pipe 4, the upper needle valve 21 may be unseated so as to cause a quantity of water to pass through the branch 9^a and enter the bowl 14 until the water level extends above the lower valve seat. Therefore, 10 the discharge passage 15 will be below the water level and no air will be permitted to enter the passage.

Should it be desired to supply only a 15 priming fluid to the pipe 4 and consequently the intake manifold, the upper needle valve 21 is closed and the lower needle valve is opened so that when a quantity of priming fluid is introduced into the bowl 14, the same will flow through the passage 15 and the 20 pipe 4.

I claim:

1. In a sight feed device, the combination with a body provided with upper and lower spaced branches having valve seats, upper 25 and lower needle valves threaded longitudinally into said branches and engaging the valve seats of the same, said body being

provided with inlet means in communication with said upper branch and with discharge means in communication with said 30 lower branch, said lower branch being provided with an open bowl extending below said lower needle valve and the valve seat of the same, the space between said upper and lower branches being entirely unobstructed to permit a priming fluid to be introduced into said bowl.

2. In a sight feed device, the combination with a body provided with upper and lower spaced branches having valve seats, upper 40 and lower independently adjustable needle valves threaded into said branches and engaging the valve seat of the same, said lower branch being provided with an open bowl extending below said lower needle valve and 45 the valve seat of the same, the space between said upper and lower branches being entirely unobstructed to permit a priming fluid to be introduced into said bowl.

3. The construction set forth in claim 2, 50 said upper branch being provided with a depending nipple directly above and in spaced relation to said bowl.

OSCAR CARL NORTON.
